UNITED STATES PATENT OFFICE.

HENRY LIEBERT, OF MILNROW, ENGLAND.

APPARATUS FOR HARDENING ROTARY CUTTERS.

SPECIFICATION forming part of Letters Patent No. 698,121, dated April 22, 1902.

Application filed January 18, 1902. Serial No. 90,308. (No model.)

To all whom it may concern:

Be it known that I, HENRY LIEBERT, a subject of the King of Great Britain, and a resident of Milnrow, in the county of Lancaster, England, (whose post-office address is Perseverance Works, Milnrow, aforesaid,) have invented new and useful Improvements in Apparatus for Hardening Rotary Cutters, (for which I have made application for a patent in Great Britain, No. 6,978, dated April 3, 1901,) of which the following is a specification.

My invention relates to improvements in apparatus for hardening rotary cutters, such as thin milling-cutters, circular knives, or saws; and the object is to provide means whereby in the process of hardening such cutters are prevented from warping, twisting, or fracturing, the teeth or cutting edge of the cutter being only hardened by allowing the liquid used for hardening to have access to the said teeth or cutting edge only. I attain this object by the mechanism illustrated in the accompanying two sheets of drawings, in which—

Figure 1 is a vertical section, partly in view, of a hardening apparatus constructed in accordance with my invention complete. Figs. 2 and 4 are side views of details; Fig. 3, a plan of Fig. 2, and Fig. 5 a plan of Fig. 1.

Similar letters refer to similar parts throughout the various views.

In carrying out my invention and referring to the figures generally I place the cutter *a* to be hardened between two disks *b* *c*, employed in a slightly-conical vessel *d*, adapted to be rotated with the said disks and cutter in a second but stationary vessel *e*, the top of which has a rim *f*, reaching over the top into the inner vessel *d*. The inner vessel *d* and disks are mounted upon the upper end of a vertical shaft *g* and jointly rotated therewith, for instance, in the following manner: The bottom *h* of the vessel *d* is formed with an inwardly-projecting boss *i*, whereby the said vessel is secured to the top of the shaft *g*. This boss is formed with a shoulder *k*, onto which the bottom disk *c* is secured. The shaft *g* is mounted in the bearings *l* and *m*, the former being formed with a stuffing-box on the bottom *n* of the second vessel *e*. In order to facilitate the placing of the cutter

to be hardened between and the removing of the same from the said two disks, I provide a spindle *o* (see more particularly Figs. 1 and 4) in or about the middle furnished with a boss *t*, having externally a flat spring *p* (or springs) secured, adapted to engage in the bore of the cutter, and thus hold same in position thereon. The upper end of this spindle serves as a handle *q*, while the lower end enters a socket *r*, formed in the shaft *g*, which carries and rotates the said disks and inner vessel, while the upper disk *b* is formed with a hole *s*, corresponding in diameter with the exterior diameter of the boss *t*, so as to allow of placing the said upper disk concentrically upon the cutter *a* and the said lower disk *c*. The said disks are so much less in diameter than the cutter to be hardened that the teeth or cutting edge of the latter only are exposed and project therefrom. In order to prevent the cutter to be hardened being chilled by the cold surfaces of the said disks and also to prevent the liquid used for hardening when rushing against the teeth or cutting edge splashing against the cutter body, the said surfaces are furnished with asbestos or the like non-combustible, non-heat-conducting, or refractory material *u*, employed in annular grooves *v*, formed in the same.

The interior diameter of the inner vessel *d* and the diameter of the rotary cutter *a* are such as to leave an annular space *w* between the same, while in the bottom *h* of the said inner vessel radial buckets *x* are formed, which communicate with the second vessel *e*. The said second vessel serves for the reception of the liquid necessary for hardening—say oil, water, or mercury—and is furnished with overflows *y*, whereby the quantity of liquid used can be kept uniform. The said overflows may communicate with a third vessel or trough *z*, formed around the second vessel *e*, adapted to receive the superfluous liquid, or the latter may be run off in any other suitable manner. The suction created by the rotation of the inner vessel *d* causes the liquid used for hardening to be raised from the second vessel *e* and be continuously circulated through the annular space *w* between the interior of the inner vessel *d* and periphery of the disks *b* *c*, the centrifugal force keeping the liquid always against the interior

of the inner vessel *d*. By this means a constant flow of fresh cold liquid is rushed past the teeth or cutting edge of the cutter to be hardened, the thickness of this belt of liquid being regulated by the speed of the rotating vessel *d* and the quantity of liquid admitted into the second or stationary vessel *e*.

The shaft *g*, carrying the inner vessel *d*, disks *b c*, and cutter *a*, may be rotated in any suitable manner, preferably by means of a friction-clutch *l*, which permits of instantly interrupting the rotation of the same when required.

What I claim as my invention, and desire to secure by Letters Patent, is—

1. In apparatus for hardening rotary cutters, a vertically-mounted shaft, a vessel and two disks on the same, an annular space between the interior of the said vessel and the peripheries of the said disks, and means for rotating the said shaft, the said disks being adapted to receive between them the cutter to be hardened and to rotate with the said shaft and vessel and the said space forming a passage for the hardening liquid, all combined substantially as and for the purpose set forth.

2. In an apparatus for hardening rotary cutters, a vertically-mounted shaft, a vessel and two cutter-holding disks on the same, a sec-

ond vessel surrounding the first-named vessel, buckets in the bottom of the latter and an annular space between the peripheries of the said disks and the interior of the said first vessel and means for rotating the said shaft, the said second vessel holding the hardening liquid and the said buckets raising and circulating it from the latter through the said annular space against the teeth or cutting edge of the cutter to be hardened, all combined substantially as and for the purpose set forth.

3. In an apparatus for hardening rotary cutters, a vertically-mounted shaft, a vessel and two cutter-holding disks on the same, an annular space between the interior of the said vessel and the peripheries of the said disks, a removable spindle in the said shaft carrying the cutter to be hardened and means for rotating the said shaft, the lower of the said disks supporting and the upper one resting upon the said cutter, all combined substantially as and for the purpose set forth.

In witness whereof I have hereunto set my hand in presence of two witnesses.

H. LIEBERT.
